OFF-PEAK WATER HEATING SYSTEM

Clark M. Osterheld, Stoughton, Wis., assignor to
McGraw Electric Company, Elgin, Ill., a corporation of Delaware

Application November 7, 1940, Serial No. 364,639

5 Claims. (Cl. 219—39)

My invention relates to electric water heating systems and particularly to off-peak water heating systems, particularly applicable for domestic hot water tanks.

An object of my invention is to provide a relatively simple heater energization delaying means subject to time and to tank water temperature for causing a predetermined delay in the energization of the heater at the start of an off-peak period in case a predetermined part of the water content of the tank is hot.

Another object of my invention is to provide a heater energization delay switch which is opened by electromagnetic means and permitted to return slowly to closed position, the delay being effected by a suitable delay gear train.

Other objects of my invention will either be apparent from a description of one form of system now preferred by me or will be pointed out in the course of such description and set forth in 15 the appended claims.

In the single sheet of drawings,

Figure 1 is a diagram of connections of my improved system as applied to an ordinary domestic hot water tank, and,

Fig. 2 is a generalized view, in side elevation, of an auxiliary control switch.

In the case where public utilities provide electric current of a district, particularly an urban district, it is usually desired by the operators to provide a load for the supply circuit or distribution system that shall be connected thereto at the time of reduced total load connected to the system. Where a lighting load constitutes a relatively large part of the total load, it is evident that this total load will be a minimum during the later hours of the night, say, approximately, from 1 o'clock to 5 o'clock or so in the morning.

The ordinary off-peak water heating system which starts energization of the electric hot water tank heaters at the start of the off-peak period, which may be at 10:00 p. m. or 11:00 p. m., means that the heater will be disconnected upon all of the water in the tank being hot at an early hour in the night, say 2 o'clock or 3 o'clock, so that the water heater load will not be present and connected to the system at the time of the occurrence of the most pronounced dip or valley in the load curve.

A hot water tank 11 is illustrated as being of the elongated cylindrical type usually used in domestic hot water installations and may be provided with a cold water inlet pipe 13 connected therewith at the bottom, an outlet hot water pipe 15 connected therewith at the top and may be 55

covered with a mass 17 of heat insulating material which, for protective purposes, may be encased by an outer casing 19. All of these elements are old and well known in the art and variations may be made therein without departing from the spirit and scope of my invention since they form no part of the present invention.

I provide an electric heater 21 for the tank which heater may be of generally annular shape and extend peripherally around the tank near the lower end thereof, being positioned in a tunnel 23. Reference may here be made to my Patent #2,226,526 issued December 24, 1940, which discloses and claims a tank heating element which I may use in this system.

I provide a main thermally actuatable switch 25 responsive to the temperature of the water in the tank near the lower part thereof. This switch includes a tubular member 27 which is secured to the wall of the tank 11 in a fluid-tight manner to be positioned within the tank. It includes also an expansion rod 29 adapted to engage with a resilient contact arm 31 normally yieldingly biased out of engagement with a relatively rigid contact arm 33 but adapted to be moved out of engagement therewith when expansion rod 29 has been expanded by reason of the subjection of tubular member 27 to the high temperature of hot water. While I have shown a specific position of the heater 21 and of the thermally actuatable switch 25, I do not desire to be limited thereto, the only object being to ensure that thermal switch 25 will not effect disengagement of contact arms 31 and 33 until substantially all 35 of the water in the tank is hot.

I provide also a continuously operative timer or timing means 35 which includes a continuously operable electric synchronous motor 37 which is electrically connected with supply circuit conductors 39 and 41 which are to be considered as being energized continuously. A worm gear 43 is operated by the motor 37, this gear engaging a worm wheel 45, this power drive being so designed, constructed and adjusted that the worm wheel 45 makes one revolution in twenty-four hours.

A worm wheel 45 is mounted on a shaft 47 which shaft has also mounted thereon a cam disc 49, the greater part of the periphery of which is of uniform outer radius but which has a peripheral portion 51 thereon of somewhat greater outer radius. The peripheral extent of the part 51 is that corresponding to the desired length of off-peak period and, for purposes of illustration, is here shown as being of substantially one-

third the total periphery, that is, the length of off-peak period is substantially eight hours. If it be further assumed that the operators of the power station supplying current to this system consider that the start of an off-peak period should be at 10:00 p. m., it is evident that the end of the off-peak period will be at substantially 6:00 a. m.

While I have hereinbefore set forth that the worm wheel 45 and therefore the shaft 47 should rotate through one complete revolution in twenty-four hours, it is obvious that speed-reducing gear wheels not shown in the drawing may be provided to cause only the cam disc 49 to rotate once in twenty-four hours. It is, therefore, to be understood that the showing of the continuously operative timer 35 is mainly for illustrative purposes and I may use any other form of continuously operative timer effective for the same general purpose.

I provide a main timer-controlled heater switch 51 which includes a relatively rigid contact arm 53, and a resilient contact arm 55, normally yieldingly biased out of engagement with contact arm 53 but adapted to be moved into engagement therewith when the leading end of part 51 of the cam disc 49 engages a lug 57, preferably made of electric insulating material, which is mounted on the arm 55 near its outer end. I provide further a heater-energization delay means including a pair of fixed contact members 59, a contact bridging member 61 which is insulatedly mounted on a lever arm or bar 63 which is turnably mounted on a shaft 65 of a delay gear train 61, the operation of which will be set forth in due course. I provide further a fixed electromagnetic coil 69 which is adapted to magnetically energize a movable core member 71 which is connected by a link 73 to the arm 63, in a pivotal manner.

The delay gear train mechanism is shown schematically or generally only since I may use any of the several devices of this kind now on the market or shown in earlier patents, and I will, therefore, describe only the operation thereof as applied to my improved water heating system. It is desired, under certain operating conditions, to energize the coil 69 with resultant quick upward movement of core 71 into an upper position in which the lever arm 63 will occupy the position shown by the broken lines and at which time the contact bridging member 61 will be out of engagement with the fixed contact members 59. Any suitable or desired stop means may be provided to limit the counter-clockwise turning movement of arm 63 and I have therefore shown a stop pin 75 although any other means effective for the same purpose may be employed.

After arm 63 has been moved to its upward position, as hereinbefore described, it is to be permitted to return slowly to the normal, closed position, as shown by the full lines in Fig. 1 of the drawing, and the time required for such return is fixed by the adjustable delay gear train which may be of any suitable or desired kind including an escapement to cause slow rundown of the gear train as driven by the lever 63 having connected therewith the contact bridging member 61 and the core member 71 and an additional weight if necessary. I may, of course, use a spring-driven gear train which is wound up by the counter-clockwise turning movement of lever arm 63 and I prefer to use a delay gear train structure which will permit of varying the run-

down period within certain general limits so that I can obtain a delay of say two hours or of three hours by movement of an adjusting arm 71, all in a manner well known in the art.

The supply circuit conductor 39 is connected to contact arm 55 by a conductor 79 and the contact arm 53 of switch 51 is connected to one of the fixed contact members 59 by a conductor 81. The other fixed contact member 59 is connected by a conductor 83 to one terminal of the heater 21, while the other terminal thereof is connected by a conductor 85 to contact arm 33. The other contact arm 31 of the main terminal switch 25 is connected by a conductor 87 to the other supply circuit conductor 41.

I provide an auxiliary thermally actuatable switch 89 responsive to tank water temperature in an upper part of the tank and this switch includes a tubular member 91, an expansion rod 93, a relatively rigid contact arm 95 and a resilient contact arm 97 normally yieldingly biased out of engagement with contact arm 95 but moved into engagement therewith when tubular member 91 and expansion rod 93 are subject to the relatively high temperature of hot water.

I provide further an auxiliary circuit-controlling means for coil 69 which I have shown generally in Fig. 2 of the drawing as including a support 99, of channel shape, which has slidably movable therein a preferably vertically extending rod 101. This rod has mounted thereon a contact member 103 adapted to be moved into and out of engagement with a fixed contact member 105. The rod 101 has also mounted thereon a flat member 107 which is spaced a suitable distance from the contact member 103 for a purpose which will presently appear.

I provide also a second circuit-controlling switch for coil 69, including a pair of normally disengaged contact arms 109 and 111 adapted to be moved into engagement with each other at the start of an off-peak period by a short cam face 113, the peripheral extent of which may be on the order of say five or ten minutes. The exact time-extent of cam surface 113 is relatively immaterial so long as its time-extent is less than the shortest possible time providable by the delay gear train 61.

Conductor 81 is connected to one terminal of coil 69 by a conductor 115 while the other terminal of coil 69 is connected by a conductor 117 with the movable contact member 103. The fixed contact member 105 is connected by a conductor 119 with contact arm 109. Contact arm 111 is connected by a conductor 121 with contact arm 95 of the auxiliary thermal switch 89 and contact arm 97 is connected by a conductor 125 with contact arm 33 of the main thermal switch.

Let it be assumed that at 10:00 p. m. the continuously operative timer has moved the cam disc 49 to the position shown in Fig. 1 of the drawing to thereby cause engagement of contact arms 55 and 53 and also of contact arms 109 and 111. Before such engagement was effected, the lever arm 63 and the parts secured thereto were in the position shown in the full lines in Fig. 1 of the drawing so that contact member 103 on the movable rod 101 was in engagement with fixed contact member 105 whereby an energizing circuit through coil 69 was provided as soon as arms 109 and 111 were engaged with each other and in case the upper auxiliary thermal switch 89 was subject to the temperature of hot water 75 in the tank with attendant engagement of con-

tact arms 97 and 95. This energizing circuit is as follows: From supply circuit conductor 39, through conductor 79, through engaged contact arms 55 and 53, through conductors 81 and 115, through coil 69, through conductor 117, through engaged contact members 103 and 105, through conductor 119 through engaged contact arms 109 and 111, conductor 121 through engaged contact arms 97 and 95, through conductor 125, through engaged contact arms 33 and 31 and from there through conductor 87 to the other supply circuit conductor 41. This will result in a quick upward movement of core member 71 and attendant quick turning movement, in a counterclockwise direction, of lever arm 63 and the distance between members 103 and 107 is such that when lever arm 63 has reached substantially its upper position, as shown by the broken lines in Fig. 1 of the drawing, the left-hand end of lever arm 63 will engage member 107 to effect slight downward movement of rod 101 and disengagement of contact member 103 from contact member 105. This will result in deenergizing the coil 69 and, as hereinbefore set forth, will now permit slow return movement of lever arm 63 in a clockwise direction, this arm reaching the position shown in the full lines in Fig. 1 of the drawing after a predetermined delay period which, for illustrative purposes, may be assumed to be two hours. It is therefore evident that at say approximately 12:00 p. m., a heater circuit through the heater 21 will be closed as follows: From supply circuit conductor 39, through conductor 79, through the engaged contact arms 55 and 53, through conductor 81, through the engaged contact members 59 and 61, through conductor 83 and heater 21, through engaged contact arms 33 and 31 and from there through conductor 87 to the other supply circuit conductor 41.

It is, therefore, evident that in case a predetermined fractional part of the water content in the tank is hot at the start of an off-peak period, with attendant subjection of the upper thermal switch 89 to hot water, an energizing circuit through the electromagnetic coil 69 is provided resulting in opening of the heater energizing circuit just above described with delayed closing of such heater circuit after a length of time adjustable by the operator or the user of such a system.

The auxiliary timer-controlled switch including the contact arms 109 and 111 will have been moved to open position within a short time after the start of an off-peak period, so that when lever arm 63 has moved into the position shown in the full lines with attendant engagement of contacts 103 and 105, the energizing circuit of coil 69 will not be closed so that energization of the heater 21 can continue until all of the water is hot or until the end of the off-peak period.

It is further obvious that in case the upper auxiliary thermal switch 89 was subjected to the temperature of cold water at the start of an off-peak period when contact arms 55 and 53 were moved into engagement with each other, that the above described energizing circuit of coil 69 would not be provided (since contact arms 95 and 97 would be disengaged from each other) and contact bridging member 61 would be and remain in engagement with, the fixed contact members 59 to effect immediate energization of the heater. It is therefore evident that the electromagnetically operable delay heater control means, including more particularly the contact members 59 and the contact bridging member 75

61, as well as the other elements operatively associated therewith, are effective to cause energization of the heater at a time varying in accordance with the amount of cold water in the tank. 5 That is, if more than a predetermined amount of cold water is in the tank at the start of an off-peak period, the heater will be energized at the start of such a period but if less than such an amount of cold water is present in the tank, energization of the heater will be delayed for an adjustably preset fixed length of time.

10 It is, therefore, obvious that my improved system provides means tending to have the energization of a tank water heater occur during the 15 more pronounced dip or valley usually occurring in a load curve during the later hours of the night, that is, from say 2:00 a. m. to 5:00 or 6:00 a. m.

20 Various modifications may be made in the system embodying my invention as herein shown and described and all such modifications clearly coming within the scope of the appended claims are to be considered as being covered thereby.

I claim as my invention:

25 1. An off-peak water heating system for a tank having an electric heater, comprising a continuously operative timer, a normally-open main-heater-control switch adapted to be moved into and held in closed position by the timer during an off-peak period, an electromagnetically-actuable normally-closed heater-control switch controlled in accordance with time and tank water temperature at an intermediate point in the tank to selectively cause opening of said 30 normally closed heater control switch for a predetermined fixed length of time at the time of closure of said main switch by the timer at the start of an off-peak period in case a predetermined fractional part of the water content of the tank is hot and to cause said switch to remain closed in case less than said predetermined fractional part of the water content is hot.

35 2. An off-peak water heating system for a hot water tank having an electric heater, comprising a main normally-open heater-control switch adapted to be held closed during an off-peak period of predetermined length, a second normally-closed heater-control switch in series electric circuit with said main switch, time and tank water temperature controlled means for 40 selectively causing opening of said second heater control switch at the start of an off-peak period in case a predetermined fractional part of the water content of the tank is hot and reclosing of said second switch after a preset fixed delay period and causing said second switch to remain closed in case a predetermined fractional part of the water content of the tank is cold.

45 3. An off-peak water heating system for a hot water tank having an electric heater, comprising a tank water temperature responsive heater-control switch movable to open position when substantially all of the water in the tank is hot, a normally-open heater-control switch, a continuously operative timer adapted to move the normally open heater control switch into and hold it in closed position during an off-peak period only, an auxiliary switch adapted to be moved into closed position momentarily by the timer at the start of an off-peak period, a normally-closed heater-energization delay switch 50 electrically connected in series circuit with said heater-control switches, an auxiliary tank water temperature controlled switch, electromagnetic means controlled jointly by said auxiliary timer-

controlled switch and said auxiliary temperature controlled switch to selectively cause opening of said normally-closed heater energizing switch at the start of an off-peak period for an adjustably preset length of time in case a predetermined fractional part of the water content of the tank is hot and to cause said normally-closed switch to remain in closed position in case less than said predetermined fractional part of the water content of the tank is hot, heater deenergization being effected selectively by the tank water temperature responsive heater-control switch in case substantially all of the water in the tank is hot before the end of an off-peak period and by the normally-open timer-actuated heater-control switch at the end of an off-peak period in case less than the full water content of the tank is hot at the end of an off-peak period.

4. An off-peak water heating system for a tank having an electric heater, comprising a continuously operative timer, a normally open main heater control switch adapted to be moved into and be held in closed position by the timer during an off-peak period, a normally closed heater control switch, an electromagnet for causing opening of said normally closed switch, means for causing energization of said electromagnet comprising a thermal switch subject to tank water temperature at an upper point of the tank and a normally open switch adapted to be closed

10 momentarily by the timer at the start of an off-peak period, energization of the electromagnet and opening of said normally closed heater switch being effected at the start of an off-peak period in case the thermal switch is subject to cold water and means for maintaining said normally closed heater control switch in open position for an adjustably preset time interval.

5. An off-peak water heating system for a tank having an electric heater, comprising a continuously operative timer, a normally open heater control switch adapted to be moved into and held in closed position by the timer during an off-peak period, a normally closed heater control switch in series electric circuit with said timer-controlled heater control switch, an auxiliary switch adapted to be moved momentarily into closed position by the timer at the start of an off-peak period, a thermal switch subject to tank water temperature, electromagnetic means controlled jointly by said auxiliary timer-controlled switch and said thermal switch for causing opening of said normally closed heater-control switch for a preset fixed time interval in case said thermal switch is subject to hot water and for preventing opening of said normally closed heater control switch in case said thermal switch is subject to cold water.

CLARK M. OSTERHELD.
